UNITED STATES PATENT OFFICE.

NATHAN JOSEPH, OF SAN FRANCISCO, CALIFORNIA.

DESIGN FOR BADGES.

Specification forming part of Design No. 5,236, dated August 29, 1871.

To all whom it may concern:

Be it known that I, NATHAN JOSEPH, of San Francisco, in the county of San Francisco and State of California, have invented a new and original Design for a Badge; and I do hereby declare that the following is a full, clear, and exact description thereof, which will enable others skilled in the art to make and use the same, reference being had to the accompanying drawing forming part of this specification.

The nature of my improved design is fully represented in the accompanying drawing, to which reference is made.

I claim as my invention—

The design for a badge, as shown.

NATHAN JOSEPH.
